UNITED STATES PATENT OFFICE.

HERBERT E. MARKS, OF GLEN OSBORNE, SEWICKLEY, PENNSYLVANIA.

ROOF OR FLOOR CONSTRUCTION.

Application filed April 14, 1922. Serial No. 552,490.

To all whom it may concern:

Be it known that I, HERBERT E. MARKS, a citizen of the United States, and a resident of Glen Osborne, Sewickley, in the county 5 of Allegheny and State of Pennsylvania, have invented a new and useful Improvement in Roof or Floor Constructions, of which the following is a specification.

This invention relates to roof or floor constructions of the type in which cast slabs of cementitious material are supported on parallel spaced flanged bars or beams,—and in which metal mesh reinforcement or its equivalent is embedded in the cementitious 15 slabs.

The object of the present invention is to increase the strength of such roof or floor constructions by locking together the reinforcing members at the contiguous ends of 20 adjacent slabs to form a continuous reinforcement for the entire length of a panel of slabs.

Generally stated, the invention consists in having the reinforcements of the slabs project beyond their ends, and providing means for interlocking with such projecting portions to connect the reinforcement of adjacent slabs whereby to form a continuous reinforcement.

30 In the accompanying drawings Fig. 1 is a plan view of a portion of a roof construction, partly broken away, showing one form of the invention; Fig. 2 is a longitudinal section on the line 2—2, Fig. 1; Fig. 3 shows 35 one of the joints of Fig. 2 on an enlarged scale; Fig. 4 is a detail view illustrating the manner of connecting the reinforcing members; and Fig. 5 is a fragmentary sectional view showing the finishing sheet on the lower 40 face of the cementitious slabs.

The drawings illustrate the invention applied to a roof construction, but it can be applied in an exactly similar way to a floor construction. In the drawings 1 represents 45 the main beams of the structure, which in the case of a roof will be the purlins. 2 are flanged bars supported on the main beams or purlins, and spaced in parallelism and at distances apart equal to the width of the cementitious slabs. These bars are shown as T-bars having their legs extending upwardly and having laterally projecting flanges 4 at their bases. Any equivalent bars having lateral projecting flanges below their upper 55 edges will answer the same purpose.

5 indicates the cementitious slabs, which

will be cast in now well known ways, of a width approximately equal to the distance between the flanged bars 2 and of any convenient or desired length. They are supported by the bars 2 by resting on the lateral projecting flanges 4 thereof.

These cementitious slabs have embedded therein a suitable metal reinforcement, which may be of any suitable kind providing only it has members extending substantially longitudinally of the slab. It is illustrated as an open metal mesh comprising longitudinal or strand wires or rods 6 and cross or stay wires or rods 7 secured to the longitudinal wires or rods preferably by electrically welding the same thereto. The reinforcement is of a length slightly greater than the length of the slabs so that the longitudinal or strand members thereof project beyond the ends of the slab to such distances that when the slabs are placed in position said projecting ends will overlap. The longitudinal reinforcement members 7 are provided with hook-like end portions 8, 80 which are interlocked with those of the adjacent slab and thus serve to connect the longitudinal members to form a continuous reinforcement. These hook portions preferably will be formed in the longitudinal 85 members before embedding the reinforcement in the cementitious material, thus insuring that the hook portions of all of the longitudinal members of a slab are in alignment transversely of the slab. Consequently when these members are hooked together all of the hook connections will interlock 90 with equal closeness, so that all of the longitudinal members will be effective as tension members.

95 In order to facilitate connecting these joints when laying the slabs in place, the ends of the hooks at one end of the slabs may be left open, as indicated in Fig. 4, so as to more readily slip into the hooks of the connecting members. Said open hooks may be afterwards closed, if desired, by a suitable tool. It is not necessary, however, that the hooks be closed, as both sets of hooks may be sufficiently open to permit of their ready 105 interlocking.

In order to provide a finish on the lower face of the roof or floor at the joint, a metal member 10 is placed transversely between the parallel bars 2, and of sufficient width to 110 effectively overlap the joint and conceal the same. Preferably this member will be of T-

form in cross section so as to give it sufficient stiffness to hold rigidly in position. It may also serve, by making it sufficiently heavy, as a support for the ends of adjacent slabs.

5 In laying a sloping roof the slabs at the ridge will be first placed in position, secured in place, and the succeeding slabs lower down will be successively placed in position, the ends of the projecting reinforcements 10 hooked together, and thus in a sense the succeeding slabs hung onto the upper slabs. In this way all slack is taken up and the reinforcement is put in initial tension, so that in the complete structure the reinforcement 15 becomes effective as a tension member. In laying a flat roof or floor, the initial tension can be secured by securing one slab in position, then laying the next slab in place, hooking the projecting ends of the reinforcement 20 together, and then moving the last laid slab longitudinally until all slack is taken up.

After the slabs are properly positioned the gaps between adjacent slabs are filled with grouting, as shown at 12, entirely 25 closing said gaps and embedding the joint, and in effect forming a continuous cementitious slab.

For roof and floor constructions in which the lower faces of the cementitious 30 slabs are exposed, the slabs will be provided with a suitable fibre facing, such as a sheet of strong paper or the like, as shown at 15, Fig. 5. This facing can conveniently be applied by placing a sheet of paper or the 35 like in the bottom of the slab mold and then casting the slab onto said sheet. Such finishing sheet gives a smooth slightly finish to the lower face of the roof or floor structure. It also does away with the necessity 40 of carefully brushing off the more or less loose particles from the lower faces of such slabs, which is now done to prevent them from dropping down into the room below. Even with careful brushing, or "dusting" 45 as it is called, some particles afterwards become detached and fall down. The finishing sheet entirely prevents this.

Preferably the slabs 5 are provided with cored out openings or passages between 50 their top surface and the metal reinforcement, in order to reduce their weight. Preferably these openings or passages will extend lengthwise of the slabs, that is, parallel to the longitudinal or strand members 6 of the reinforcement, and are located midway therebetween as shown at 16, Figs. 3 and 5, thereby leaving the portion of the 55 slab directly overlying the strand wires unbroken and intact for effectively distributing the strains throughout the entire structure. Such openings will be formed in the molding of the slabs by the use of suitable withdrawable cores, as will be readily understood.

60 Manifestly in lieu of the purlins and

parallel T-bars shown, various frame constructions may be used to support the slabs. Indeed the slabs may be supported directly by the main beams of the roof or floor structure, by spacing of the main beams so 70 as not to exceed the width or length of the slabs.

The roof or floor construction described is simple, easy to erect and gives maximum strength for the amount of material used. 75 While the slabs are individually cast, the locking together of the ends of the reinforcement of adjacent slabs provides a continuous reinforcement from end to end of the panel. 80

I claim:

1. A roof or floor construction comprising supporting bars, cementitious slabs resting on said bars, metal reinforcement embedded in said slabs and having longitudinal members projecting beyond the ends of said slabs, said projecting ends being bent transversely of the axes of said members and interlocked with the bent ends of the longitudinal members of contiguous slabs to 85 form a continuous reinforcement, a fibre sheet closely adhering to the lower surface of the slabs, a transverse member disposed within the gap between contiguous slabs and provided with laterally projecting portions underlying the edges of said contiguous slabs whereby to present a finished appearance and to prevent the separation 90 of the fiber sheet from the body of the slab adjacent the said edges. 100

2. A roof or floor construction comprising supporting bars, cementitious slabs resting on said bars, metal reinforcement embedded in said slabs and having longitudinal members projecting beyond the ends of said slabs, said projecting ends being bent transversely to the axes of said members and interlocked with the bent ends of the longitudinal members of contiguous slabs to 105 form a continuous reinforcement, a fiber sheet closely adhering to the lower surface of the slabs, an inverted T-shaped transverse member having its web portion disposed within and bridging the gap between contiguous slabs and its laterally projecting base portions underlying the edges of said contiguous slabs whereby to present a finished appearance and to prevent the separation of the fiber sheet from the body of the slab adjacent the said edges, 110 and grouting filling the gaps between said slabs. 115

3. A roof or floor construction comprising supporting bars, cementitious slabs resting on said bars, metal reinforcement embedded in said slabs and having spaced parallel longitudinal members projecting beyond the ends of said slabs, the body of the slab being provided with cored out 125 passages disposed in vertical planes interme- 130

diate the longitudinal members whereby to leave the portion of the body overlying the said longitudinal members unbroken, said projecting ends being bent transversely 5 to the axes of said members and interlocked with the bent ends of the longitudinal members of contiguous slabs to form a continuous reinforcement, a fiber sheet closely adhering to the lower surface of the slabs, 10 a transverse member disposed within the gap between contiguous slabs and pro-

vided with laterally projecting portions underlying the edges of said contiguous slabs, whereby to present a finished appearance and to prevent the separation of the 15 fiber sheet from the body of the slab adjacent the said edges.

In testimony whereof, I sign my name.

HERBERT E. MARKS.

Witness:

EDWIN O. JOHNS.
